UNITED STATES PATENT OFFICE.

LEONARD MILLER, OF BROWNSWOOD, TEXAS.

MOTOR.

1,134,147.

Specification of Letters Patent.

Patented Apr. 6, 1915.

Application filed May 5, 1914. Serial No. 836,514.

To all whom it may concern:

Be it known that I, LEONARD MILLER, citizen of the United States, residing at Brownwood, in the county of Brown and State of Texas, have invented certain new and useful Improvements in Motors, of which the following is a specification.

This invention relates to motors and has for its object the provision of a compact and simply arranged mechanism by which the expansive power of metal may be utilized to drive machinery.

A further object of the invention is to provide means whereby a metal bar or series of bars may be alternately subjected to heat and cold so as to be successively expanded and then contracted and the consequent lengthening and shortening of the bar utilized to apply power.

A further object of the invention is to provide means for automatically controlling the passage of the heating and cooling agents to the bar or bars, and a further object of the invention is to provide means for overcoming a dead-center should the motor come to rest at such point.

The several stated objects of the invention, and such other objects as will incidentally appear from the following description, are attained in such a mechanism as is illustrated in the accompanying drawings, and the invention consists in certain novel features which will be particularly pointed out in the claims following the description.

In the drawings, Figure 1 is a front elevation of a motor embodying my present invention; Fig. 2 is a rear elevation of the same; Fig. 3 is an end elevation thereof; Fig. 4 is a detail view of the starting mechanism; Fig. 5 is a longitudinal section; Fig. 6 is an end view of one of said bars; Fig. 7 is a horizontal section taken on the line 7—7 of Fig. 1.

In carrying out my invention I employ an upright standard or frame 1 which is secured rigidly upon a base 2 and suitably braced by webs or diagonally disposed frames 3. The main frame or standard 1 is open through its center so as to accommodate the moving parts and connections and may, of course, be of any desired size. At the front and rear of the said frame I arrange a plurality of hollow metal bars 4 which are preferably of aluminum and are connected in a series so that motion may be transmitted from one end of the series to the

other, and at the latter end utilized to operate a movable member. A lever 5 is fulcrumed at one end to an upper corner of the main frame, as indicated at 6, and one of the end bars 4 is pivotally connected to the said lever adjacent its fulcrum by means of a split collar 7 carried by the said bar and secured around a pin 8 projecting from the lever. The bars may be of any desired number and in the present instance I have shown six bars at each side of the main frame, the end bar at the rear of the frame and adjacent the fulcrum of the lever 5 being attached at one end to a fixed stud or resistance block 9. The said bar has a threaded post or stem 10 secured in its upper end, as clearly shown in Fig. 2, and the said stem or post projects through the said resistance block 9 so as to extend above the same. A spring 11 is coiled around the stem above the said block and an adjusting nut 12 is fitted upon the stem above the spring so as to regulate the tension thereof. A nut 13 is fitted upon the stem below the resistance block and is adapted to bear against the said block so as to receive the motion of the bar, the spring 11 tending to maintain the nut 13 against the resistance block and also serving as a governor to prevent spasmodic or uneven movement of the parts. The lower end of the said bar carries a bracket 14 terminating in a split collar 15 which fits around a stud 16 at one end of a lever 17 which is fulcrumed upon the lower portion of the frame 1. The opposite end of the said lever is provided with a similar crank pin 18 to which is fitted the lower end of the next adjacent motor bar, as clearly shown in Fig. 2. The upper end of the said second motor bar is similarly connected with a lever 19 which forms a connection between the said bar and the other motor bar and is suitably fulcrumed upon the upper portion of the main frame. The same form of connection is utilized throughout the series so that each bar is connected at its lower end to a bar at one side, and at its upper end to the bar at the opposite side. The bar at that end of the series more remote from the initial bar, which will, for convenience, be referred to as the anchor bar and is connected to the resistance block 9 in the manner shown and described, is disposed somewhat obliquely and has its upper end connected to one crank 20 of an angle lever 21 which is ful-

crummed in and extends through the upper portion of the main frame and is provided at its front end with a second crank arm 22. The said crank arm 22 is connected with the 5 upper end of a motor bar at the front of the main frame and the lower end of this motor bar is connected with a lever 23 which serves to connect it with the lower end of the next adjacent motor bar. The motor 10 bars at the front of the frame are thus connected at their upper and lower ends in the same manner as the bars at the rear of the frame, and the end bar of the series is connected to the lever 5, as previously stated. 15 It will be readily noted that when the several bars are highly heated and thereby expanded, the lengthening of the bars will tend to swing the several connecting levers about their fulcrums so that the crank arms 20 of the levers will swing through arcs, the amplitude of which successively increase from the lower end of the anchor bar to the power applying bar which is connected to the lever 5 so that, while the crank arm at 25 the lower end of the anchor bar may have a very slight and almost imperceptible movement, the movement of the lever 5 will be very pronounced. The free end of the lever is connected through suitable mechanism 30 with the machinery to be driven.

In Figs. 5 and 6 I have illustrated in detail the construction of the hollow motor bars. As clearly shown in the said figures, passages 24 are formed longitudinally 35 through the said bars so that the heating and cooling agents circulate freely through the bars, while at the same time the bars will have sufficient substance to possess the necessary strength to apply the power generated and to resist buckling or bending under the successive variations of the temperature. It will be readily seen that the longitudinal passages 24 are arranged through the axial center of the bars and also at points 40 spaced from the center but out of radial alignment so that webs will be left between the adjacent openings or passages to guard against collapse of the bars. To facilitate the communication between the passages transverse 45 50 openings 25 may be provided at various points within the bars. Each bar has a cap 55 fitted upon its upper end and a gasket 27 is provided between the edge of the said cap and the adjacent surface of the bar so that leakage between the cap and the bar will be 60 prevented. A threaded stud 28 is secured in the end of the bar and projects beyond the same and through the cap to receive the bracket 14 carrying the split ring or collar 65 15, and the said bracket may be utilized as a clamping nut so that, if it be turned home against the cap through its threaded connection with the stud 28, the cap will be firmly clamped to the bracket 14, and a gasket 29 is fitted between the cap and the bracket

around the stud 28 so as to prevent leakage at this point, as will be readily understood. It will be readily noted upon reference to Fig. 5 that a chamber or space is provided between the cap and the end of the bar, and 70 a tube 30 leads to each bar from a common supply pipe 31 which is secured upon the rear side of the frame in any convenient or preferred manner. The construction at the lower end of the bars is identical with that 75 at the upper end just described and an exhaust tube 32 leads from the cap at the lower end of each bar to an exhaust or outlet pipe 33 which may be disposed in any convenient manner at the lower portion of the frame 80 and carried to any desired point to lead the products of condensation from the motor. A convenient disposition of the said products will be to connect the exhaust or discharge pipe with the boiler so that the water 85 may be again utilized for the formation of steam. The supply pipe 31 leads from a valve casing 34 which is arranged at the front side of the frame 1 and receives steam through its upper end from a pipe 35 90 and cold water through its lower end from pipe 36, the said pipes 35 and 36 being connected with any convenient source of supply, as will be readily understood.

The free end of the lever 5 is pivotally attached to the upper end of a pitman 37 which is pivotally attached at its lower end to a cross-head 38 slidably mounted in suitable guides or brackets 39 secured upon the front side of the main frame, as clearly shown. 100 The said cross-head is provided at or near its lower end with a stud 40 which receives the lower end of the pitman 37, and a second stud or pin 41 is provided near the upper end of the said cross-head to receive the lower 105 end of a link or connecting rod 42 which has its upper end pivotally connected with a crank pin 43 upon a crank disk 44. The said crank disk 44 is secured rigidly on the inner end of the power shaft 45 which is journaled in suitable bearings 46 upon the main frame and is equipped at its outer end with a combined band pulley and fly-wheel 47. A belt 48 is trained around the said band pulley and fly-wheel 47 and a second band pulley 49 which is carried by a shaft 50 mounted in any convenient supports upon the base 2, a gear-wheel 51 being also carried by the said shaft 50 and meshing with a pinion 52 upon a shaft which may form a part of the 110 machine to be driven or may be extended to a distant point to transmit the power. It will, of course, be understood that the pinion 52 and its shaft are not essential and the shaft 50 may be utilized as the transmission 115 shaft. A link or connecting rod 42 has its lower end secured to a boxing 53 in which are mounted the bearings 54 which fit around the stud or pin 41, as shown most clearly in Fig. 4. 120

The upper bearing 54 is provided with a stud 55 which extends into a hollow extension 56 on the upper side of the boxing 53, and a spring 57 is provided within the said hollow extension 56 so as to bear upon the stud or pin 55 and the upper end of the said extension and thereby yieldably hold the said upper bearing 54 to the stud or pin 41. Should the device come to rest upon the dead center, as indicated in Fig. 4, upward movement of the cross-head would carry the upper bearing 54 against the said spring, which would be compressed and, consequently, breakage of the parts would not occur. Between the studs or pins 40 and 41 a bracket 58 is pivotally mounted upon the cross-head and the said bracket projects forwardly from the cross-head and is provided at its front extremity with an eye 59 in which is secured a lifter or starting bar 60. This starting bar or lifter is normally held toward the cross-head by a spring 61 secured to the cross-head and engaging a clip 62 carried by the lifter, as shown in Fig. 4. The upper end of the lifter is turned laterally so as to lie at an angle to the length of the lifter and the radius of the crank disk 44 and is adapted to engage a starting pin 63 carried by the said disk. A friction roller 64 is mounted upon the said pin 63 so as to reduce the wear between the parts and also tend to overcome any liability of the lifter binding when in operation.

Assuming the parts to be in the position shown in Fig. 4, if an upward movement be imparted to the cross-head, the lifter will be carried against the pin 63 and will move the same upwardly so that the crank disk will be rotated sufficiently to carry the crank pin 43 beyond the dead center. The device will then operate in the ordinary manner and when the starting pin has completed a revolution, or is about to complete a revolution, it will ride against the under surface of the obliquely disposed portion of the lifter and will push the same aside against the resiliency of the spring 61, as will be readily understood.

An eccentric 65 is secured upon the power shaft 45 between the bearings 46 and the eccentric rod 66 extends upwardly from the eccentric to operate the valve gear. The upper end of the said rod is adjustably pivoted to a segmental gear or rack 67 which is mounted upon the forward end of a bracket 68 projecting from the frame or the valve casing 34, and the said gear meshes with a pinion or co-operating gear 69 which is rigid with the extended stem of the valve 70. As illustrated in the drawings, the valve is in a position to establish communication between the steam feeding pipe 35 and the main sup-

ply pipe 31. The steam will heat the motor 65 bars so as to expand the same and cause the power lever 5 to swing upwardly about its fulcrum, and this upward movement of the lever will be transmitted through the pitman 37 to the cross-head 38 so as to actuate the power shaft 45. The eccentric 65 will be carried around by the power shaft so as to raise the eccentric rod 66 and, consequently, the gear 67 will actuate the pinion 69 to move the valve 70 so that its port will establish communication between the supply pipe 31 and the cold water pipe 36 and cut off the flow from the steam pipe.

From the foregoing description taken in connection with the accompanying drawings it is thought that the operation of my improved motor will be readily understood. When steam is admitted to the supply pipe 31 it will flow from the said pipe through the several tubes 30 into all the motor bars so that the said bars will be simultaneously heated. As the bars are raised in temperature they will expand and the movement due to expansion will be transmitted through the several cranks and levers to the power lever 5, as hereinbefore stated, so that said lever will be moved upwardly to the limit of its stroke. As the lever moves upwardly the pitman 37 will, of course, be drawn upwardly so that the cross-head 38 will be raised and will actuate the power shaft through the link 42 and the crank disk 44, as will be readily understood. The rotation of the power shaft will carry the eccentric 65 around to its upper position so that the valve 70 will be automatically shifted to cut off the flow of steam and permit cold water to flow to the several motor bars just as the power lever reaches the upper limit of its stroke. The cold water will follow the same path the steam previously followed and will cause simultaneous action of the motor bars and cause them to contract so that the power lever will be lowered and the rotation of the power shaft will be completed. The band pulley and power wheel 47 will tend to carry the crank disk 44 past both the upper and lower dead centers, but there will be a possible tendency of the machine to come to rest upon the lower dead center owing to the gravity of the several parts, as will be readily understood. Of course, as the parts approach this lower dead center or starting point, the valve 70 will be shifted so as to cut off the flow of cold water and re-establish the communication between the steam pipe and the supply pipe.

My device is exceedingly simple in the construction and arrangement of its parts and will occupy very little space in the power plant so that it may be economically installed and may be operated without any

annoyance due to dirt or other deleterious influences.

Having thus fully described my invention, what I claim is:

- 5 1. A motor comprising a metal bar anchored at one end, a movable member operatively connected with the other end of the bar, means for supplying heating and cooling agents to the said bar, and means 65 actuated by the said movable member for controlling the said means for supplying heating and cooling agents to the bar.
- 10 2. A motor comprising a hollow metallic bar anchored at one end, a supply pipe, a connection between the said supply pipe and one end of the bar, an exhaust pipe, a connection between said exhaust pipe and the opposite end of the bar, means for admitting heating and cooling agents to the supply pipe, a movable member operatively connected with the free end of the bar, and means actuated by the movable member for controlling the means for admitting heating and cooling agents to the supply pipe. 70
- 15 3. A motor comprising a series of hollow bars, an anchor for one end of the bar at one end of the series, a movable member connected with one end of the bar at the opposite end of the series, crank shafts connecting the adjacent ends of successive bars throughout the series, and means for successively and alternately supplying heating and cooling agents to the several bars. 75
- 20 4. A motor comprising a hollow bar, an anchor for one end of said bar, a movable member operatively connected with the opposite end of the said bar, a supply pipe communicating with the said bar, a valve arranged to establish communication between the supply pipe and either the steam pipe or the cold water pipe, gears arranged to oscillate the said valve, means for actuating said gears, and operative connections between 80 said actuating means and the hollow bar.
- 25 5. A motor comprising a frame, a cross-head slidably mounted upon the said frame, a power shaft upon the frame, operative connections between the said shaft and the cross-head, a power lever fulcrumed upon the frame, a pitman connecting said lever to the cross-head, a plurality of hollow bars arranged adjacent the frame, one of said bars being anchored to the frame and another of said bars being pivotally connected to the power lever, connections between the intermediate bars movably mounted upon the frame, and means for alternately and successively supplying heating and cooling agents to the bars. 85
- 30 6. A motor comprising a metallic bar having longitudinal passages formed there- 90
- 35 in, caps secured upon the ends of the bar and spaced therefrom, an outlet tube leading from the cap at the lower end of the bar, an inlet tube leading into the cap at the upper end of the bar, and means for supplying heating and cooling agents successively to the said inlet tube. 95
- 40 7. In a motor of the character described, the combination of a metallic bar having longitudinal passages formed therethrough, threaded studs secured in the ends of the bar, caps fitted upon the said stud and spaced from and engaging the ends of the bar, inlet and outlet tubes communicating with the interior of said caps at the opposite ends of the bar, brackets fitted upon the outer ends of the studs and bearing against the caps, movable members engaged by said brackets, and means for alternately admitting heating and cooling agents to one of the caps. 100
- 45 8. In a motor of the character described, the combination of a hollow metallic bar, a supply pipe connecting with said bar, a steam pipe, a cold water pipe, a valve arranged to establish communication between the supply pipe and either the steam pipe or the cold water pipe, gears arranged to oscillate the said valve, means for actuating said gears, and operative connections between 105 said actuating means and the hollow bar.
- 50 9. In a motor of the character described, the combination of a series of hollow bars, means for supplying heating and cooling agents successively and alternately to said bars, a cross-head, operative connections between said cross-head and the hollow bars, a power shaft, a crank disk on said power shaft, a stud on the cross-head, bearings engaging said stud, a boxing inclosing said bearings, a link connecting said boxing with the crank disk, and a spring carried by the link and engaging the upper bearing. 110
- 55 10. In a motor of the character set forth, the combination of a hollow bar, means for supplying heating and cooling agents alternately and successively to said bar, a power shaft, a crank disk on said power shaft, a cross-head, operative connections between the said cross-head and the crank disk, operative connections between the cross-head and the hollow bar, a lifter carried by the cross-head, and a starting pin on the crank disk adapted to be engaged by said lifter. 115
- 60 In testimony whereof I affix my signature in presence of two witnesses.
